UNITED STATES PATENT OFFICE.

HERBERT E. HOFFMAN, OF PROVIDENCE, RHODE ISLAND, ASSIGNOR TO GENERAL FIRE EXTINGUISHER COMPANY, OF PROVIDENCE, RHODE ISLAND, A CORPORATION OF DELAWARE.

AUTOMATIC MIXING AND DISCHARGING SYSTEM FOR PLURAL LIQUIDS.

Application filed October 27, 1924. Serial No. 746,036.

This invention relates to improvements in automatic mixing and discharging systems for plural liquids. More particularly it relates to fire extinguishing apparatus whereby two liquids, adapted to react chemically upon each other to produce a fire extinguishing agent, such as fire foam, are stored in separate containers until needed, and then released simultaneously through a common discharge outlet. Heretofore it has been thought necessary to provide, in addition to the separate containers, separate pipe lines thence to some form of double outlet, as for example a sprinkler head having two orifices, one for each liquid. Owing to the corrosive properties of one of the liquids most commonly used, non-corrodible pipe has been required from the container of this liquid to the discharge nozzle, or sprinkler head; and the latter required to provide for double discharge, has also been specially treated, as by lining with lead, to avoid the ravages of the corrosive liquid.

The present invention is directed to provide apparatus which for the most part can be made up from regular stock supplies of pipe and sprinkler heads. The invention is to eliminate the need for special anti-corrosion devices and the special sprinkler heads heretofore required to provide separate valves for the two liquids. Thus it lessens at the start the installation cost; and, as will hereinafter appear, by withholding the corrosive liquid from the distributing lines until actual discharge occurs, the maintenance cost is materially reduced.

The apparatus of the invention includes the provision of separate containers for the liquids, one of which is preferably internally lined with lead in the usual way. From each container a siphon leads; and these siphons join in a common discharge pipe having an outlet through one or more single ordinary thermo-responsive sprinkler heads which may be of any one of many well known commercial types. The down or discharge legs of the siphons, and the upper ends of the entrance legs thereof, are primed with some neutral and non-corrosive liquid, as for example, water. Upon the opening of the sprinkler head, this water runs out, pulling the two liquids after it, according to the siphonic principle. As they reach the common discharge pipe the liquids

physically mix, and they become discharged before the chemical reaction between them proceeds far enough to establish any appreciable pressure. The discharge of the two liquids in mixed and reacting relation then continues until the level in each tank gets down to the entrance opening of its siphon.

A generic and simple type of embodiment of the invention is illustrated in the accompanying drawing, which shows apparatus particularly adapted for use over a vat or tank where highly inflammable material is used or stored, and the distribution system of piping is extremely short, having but a single sprinkler represented as close to the tank; but this application of the principles is merely illustrative. It is intended that the patent shall cover, by suitable expression in the appended claims, whatever features of patentable novelty exist in the invention disclosed.

In the accompanying drawing, Figure 1 is an elevation showing, in section, a tank containing the two liquids in separate compartments, and, in face view uncut, the siphons and their common discharge; and Figure 2 is an elevation, in larger scale, showing the details of the tank vent.

Referring to the drawing, the tank is divided by a partition 12 to form separate containers 14 and 16, one of which 14, has preferably a lead lining 15 in which the corrosive or acid liquid, otherwise usually known commercially as the "A" solution, is stored. The other container 16, holds the alkali or "B" solution.

From each container a siphon extends, 18, 20, delivering below the tank into a common discharge pipe 22 having a thermally-responsive valve 24, such as an ordinary automatic sprinkler head. The discharge leg 18' of the siphon 18 from the container holding the "A" solution preferably extends downward through the "B" solution. With this arrangement the use of non-corrodible pipe is necessary only for the entrance leg 18'' that stands in the "A" solution. At the crest of each siphon a removable plug 26 enables the discharge legs 18', 20' and common discharge pipe 22 to be primed with water. This may be inserted after the two containers have been filled with their respective solutions up to the normal supply level, such

as that illustrated. When thus primed, the plugs 26 are screwed into place, and the cover 28 of the tank is attached.

The cover is illustrated as being provided with a vent 30 having two check valves 32, 34, one opening for discharge from the tank and the other openable for intake to the tank. Thus is provided a slight resistance which is sufficient to retard or prevent air circulation while the apparatus is waiting ready for use; and this prevents any great amount of evaporation, yet provides relief inflow or outflow of air when caused by sufficient change of pressure due to changes of temperature within the tank, and provides for inflow of air when the apparatus operates.

The operation is extremely simple. While standing ready the intake leg of each siphon contains its own kind of liquid; its discharge leg contains the priming liquid, e. g. water; and the space above liquid levels at the crest contains air. Upon the sprinkler head opening, the water columns in the discharge legs immediately start to flow down through the common discharge pipe and the sprinkler. This fall starts the siphons working. In each the suction draws over the solution standing in its entrance leg, the small quantity of air at the top not being enough to prevent this; and thereafter the siphonic action continues until the liquid level in each tank reaches the entrance of its siphon. By making the tanks of about equal capacity, and making the liquids of suitable dilution for a full tank of each to require a full tank of the other for its complete chemical reaction, the discharge flow of the liquids may be at equal rates, thus conveniently producing the most effective formation of foam for fire extinguishing purposes, without having any considerable over-plus of either liquid to flow alone at the end.

While the valve selected for illustration, for holding the apparatus ready and for starting its discharge, is of the automatic type known as a "sprinkler head", operating at a certain temperature, it is obvious that a valve opened automatically by some other means might be used, or a valve arranged to be opened only manually. Also it will be understood that the apparatus is applicable to large tanks and that the system of distribution piping therefrom may be indefinitely long and ramified or cross connected, without requiring more than the customary single sprinkler fed by a single pipe at each outlet station, as in ordinary water systems.

I claim as my invention:

1. An automatic mixing and discharging system for plural liquids adapted to re-act

chemically upon each other comprising the combination, with separate containers for said liquids, of a siphon for discharging the liquid of each container having their discharge legs preliminarily primed with liquid, 65 said siphons being connected in a common discharge passage; and a single valve controlling the common passage adapted to be opened to effect simultaneous discharge of the plural liquids. 70

2. An automatic mixing and discharging system for plural liquids adapted to re-act chemically upon each other comprising the combination, with separate containers for said liquids, of a siphon for discharging the 75 liquid of each container having their discharge legs preliminarily primed with liquid, said siphons being connected in a common discharge passage; and thermo-responsive means normally preventing discharge but adapted at a predetermined temperature to permit simultaneous discharge of the plural liquids. 80

3. An automatic mixing and discharging system for plural liquids adapted to re-act 85 chemically upon each other comprising the combination with separate containers for said liquids, of a siphon rising from one of them and descending through the other of them; and another siphon in said other container; the discharge legs of both siphons being preliminarily primed and connected to a common discharge passage; and a valved outlet from said passage whereby upon opening the discharges from the two containers 90 occur together. 95

4. An automatic mixing and discharging system for plural liquids comprising the combination with separate containers for said liquids of a siphon for each liquid arranged for simultaneous discharge of both; means for opening the crest of each siphon, to permit of the priming of the discharge leg thereof; and a common outlet for the discharge legs having a valved closure adapted 100 to be opened for simultaneous discharge of both liquids. 105

5. An automatic mixing and discharging system for plural liquids comprising the combination of a covered holder having separate liquid containing compartments; a top vent, and valves associated with said vent providing a slight resistance to inflow and to outflow of gases; a siphon from each compartment having a common outlet providing 110 simultaneous discharge of said liquids; and means controlling said outlet. 115

Signed at Providence, Rhode Island, this ninth day of October, 1924.

HERBERT E. HOFFMAN.
